FOLDABLE WHEEL CHAIR

Monroe Arnold Lerman, Sunnyside, N. Y.

Application January 16, 1952, Serial No. 266,752

3 Claims. (Cl. 155—30)

1

This invention relates to new and useful improvements in foldable wheel chairs for handicapped persons, and has more particular reference to an adjustable seat thereof.

The width of a wheel chair is more or less determined by the width of buttocks of persons using them. The seat portion of the chair must normally be wide enough so that the user may comfortably sit therein. However, wheel chairs thus constructed are of such widths that they are too wide to pass through narrow doors. Consequently, the handicapped person cannot conveniently enter certain rooms in the home, as for example the bathroom, which usually has a door smaller than other doors. An important feature of this invention resides in so constructing the wheel chair that the person sitting therein may operate means for adjusting the width of the chair to make it possible to pass through narrow doors. It is proposed that when the chair is narrowed in width the sides of the chair will squeeze against the buttocks. However, this is not objectionable since after the chair has been moved through the narrow door it may again be widened to its natural width. It is proposed to so construct the width operating feature of this invention that it will not interfere with the normal folding of the wheel chair. Consequently the wheel chair may be folded in the usual way at any time.

It is also customary to construct wheel chairs so that a person sits at a normal height. While this height is satisfactory most of the time there are instances when the user wishes to reach up to a higher object. It is now proposed to so construct the new wheel chair that the user may elevate the seat thereof in order to reach up whenever he so desires. It is also proposed to so construct this and other elevating features that they do not interfere in any way whatsoever with the normal folding of the chair.

Arthritic persons often find it difficult to raise themselves from a sitting to a standing position. It is another object of this invention to so construct the new wheel chair that the seat thereof may be tilted upwards from the front to the back and that simultaneously the seat back of the chair moves up a corresponding distance in order to assist an arthritic person from a sitting to a standing position.

Another object of the invention is the construction of a wheel chair as described which is simple and durable and which may be manufactured and sold at a reasonable cost.

For further comprehension of the invention, 55 15, and a back forked end 22 which slidably en-

2

and of the objects and advantages thereof, reference will be had to the following description and accompanying drawings, and to the appended claims in which the various novel features of the 5 invention are more particularly set forth.

In the accompanying drawing forming a material part of the disclosure:

Fig. 1 is a side elevational view of a folding wheel chair constructed in accordance with this 10 invention.

Fig. 2 is a front view of the chair shown in Fig. 1.

Fig. 3 is a plan view of Fig. 1.

Fig. 4 is a fragmentary enlarged horizontal 15 sectional view taken on the line 4—4 of Fig. 1.

Fig. 5 is a fragmentary enlarged vertical sectional view taken on the line 5—5 of Fig. 3.

Fig. 6 is a fragmentary enlarged vertical sectional view taken on the line 6—6 of Fig. 1.

Fig. 7 is a fragmentary enlarged vertical sectional view taken on the line 7—7 of Fig. 1.

Fig. 8 is a fragmentary enlarged sectional view taken on the line 8—8 of Fig. 1.

Fig. 9 is a fragmentary enlarged horizontal 25 sectional view taken on the line 9—9 of Fig. 1.

Fig. 10 is a fragmentary vertical sectional view taken on the line 10—10 of Fig. 6.

Fig. 11 is a fragmentary enlarged vertical sectional view taken on the line 11—11 of Fig. 3.

Fig. 12 is a fragmentary enlarged vertical sectional view taken on the line 12—12 of Fig. 3.

Fig. 13 is a front elevational view of the chair as illustrated in Fig. 1, but shown in its folded condition.

Fig. 14 is a side elevational view of the chair shown in Fig. 1 but illustrated with the seat thereof in an elevated position.

The new folding wheel chair, in accordance with this invention, includes a pair of side frames 10 each having a large back wheel 11 and a small front wheel 12. Each frame 10 is also provided with a front foot rest 13 hingedly mounted in the usual way to move from a horizontal position, shown in Fig. 2, to a vertical position when the wheel chair is folded, as shown in Fig. 13. Each side frame 10 has an arm rest 14, a front vertical arm 15, and a back substantially vertical arm 16. Each side frame 10 also has a horizontal bottom arm 17. A flexible seat back 18 is mounted between said side frames 10.

A seat support member 20 is vertically slidably mounted on each of said side frames 10. Each seat support member 20 has a front forked end 21 which slidably engage the front vertical arms 15, and a back forked end 22 which slidably en-

gage the back vertical arms 16. The seat support members 20 are slidably mounted to move into vertical positions by these forked ends 21 and 22. A flexible seat 23 is mounted between said seat support members 20.

The side frames 10 are connected by foldable means adapted to hold said side frames 10 in spaced positions, as illustrated in Fig. 2, representing the open position of the chair, and closed together as illustrated in Fig. 13, representing the folded position of the chair. This foldable means includes a pair of crossed arms 25 pivotally connected at their centers by a pintle 26 and having their bottom ends pivotally connected with said side frames 10. More particularly, the bottom ends of the crossed arms 25 are connected with tubular members 27 which pivotally engage upon the horizontal bottom arms 17 of the side frames 10. The crossed arms 25 have their top ends pivotally connected with slide members 30 vertically slidably mounted upon the side frame 10. The top ends of the crossed arms 25 are provided with tubular members 31 which pivotally engage upon the sliding members 30. Each slide member 30 is provided with a forked front end 32 which slidably engage the front vertical arms 15 on the side frames 10. Each slide member 30 is also provided with a forked back end 33 which slidably engage the back vertical arms 16 of the side frames 10.

The slide members 30 are limited to bottom positions by stop pins 34 which are mounted on the vertical arms 15 and 16 of the side frames 10. These stop pins 34 determine the open position of the wheel chair. The slide members 30 may slide upwards on the vertical arms 15 and 16 when the chair is folded closed. The seat support members 20 normally rest upon the slide members 30.

The seat support members 20 are associated with means operable by a person sitting on the seat 23 for adjusting said seat support members 20 to various elevated positions for adjusting the elevation of the seat 23. This means includes telescoping members 35, 36 and 37 which are free to expand at any time in order that said slide members 30 may be moved completely upwards by said crossed arms 25 to permit folding of said wheel chair. The telescoping members 36 and 37 comprise respectively the extendable telescopic member 36 and the stationary telescopic member 37 of a hydraulic jack 38. The telescopic member 37 is rigidly connected with the base 39 of the jack 38 which is mounted upon the tubular member 27 of one of the crossed arms 25. The base member 39 has forked clamp portions 40 which engage down the sides of the tubular portion 27. Bolts 41 engage through the bottom ends of the forked portions 40. A strap 42 is connected with one of the forked portions 40 and with an adjacent stationary portion of the frame 10 for holding the jack 38 in a stationary position while permitting the tubular portion 27 to turn during the folding and opening of the chair.

The hydraulic jack 38 is provided with a handle 43 which extends upwards to a position easily reached by a person sitting on the seat 23. The handle 43 is hollow. A cable 45 passes through this handle 43 and connects at the top with a knob 46 which is turnably mounted. This knob 46 may be turned for turning the cable 45. The bottom end of the cable 45 connects with the valve control 47 of the jack 38 so that the person

may turn the knob 46 in one direction to cause the telescopic member 36 to be moved upwards by operation of the handle 43 when desired. The knob 46 may also be turned in the other direction to adjust the valve control 47 so that the weight of the person sitting on the seat 23 forces the telescopic member 36 of the jack 38 downwards.

The telescopic member 36 is provided with an arm 50 which extends downwards. A rod 51 is supported at the bottom of the arm 50. Support arms 52 and 53 are pivotally connected with the rod 51 at their bottom ends. The top ends of the support arms 52 and 53 are pivotally connected with brackets 54 mounted on one of the seat support members 20. The telescopic arm 35 is connected with the other of the seat support members 20. The telescopic arm 35 is merely vertically slidably mounted in the top of the telescopic arm 36. The arrangement is such that when the jack 38 is operated to move the telescopic member 36 upwards, the two seat support members 20 will be simultaneously moved upwards for elevating the seat 23.

The side frames 10 are associated with means operable by a person sitting on said seat 23 for slightly moving together said side frames 10 from their open positions to slightly narrower positions to narrow said wheel chair. This means merely comprises a hook 55 adapted to rigidly connect one of said slide members 30 and one of said seat support members 20. As illustrated in Fig. 6, the hook 55 is supported on a bracket 56 rigidly connected with said seat support member 20. The hook 55 has a top handle 57 by which it may be manually turned to a position indicated by the dot and dash lines 58'. In this latter position the hook 55 extends beneath the slide member 30. Now when the jack 38 is operated to elevate the seat support members 20, the slide member 30 will be forced upwards. This will cause the crossed arms 25 to be pivoted which will force together the side frames 10. The side frames 10 may be forced together so as to clamp against the buttocks of a person sitting on the seat. This represents the narrow condition of the chair in which it may be narrowed anywhere from two to five inches or more, and be capable of passing through a narrow doorway.

Said seat 23 and said seat back 18 are associated with each other and with means by which the back portion of the seat 23 may be tilted upwards and simultaneously the seat back 18 may be raised in order to assist an arthritic person from a sitting to a standing position. More particularly, the seat back 18 is provided at each of its sides with a slide 60. Each slide 60 vertically slidably engages a track 61 mounted upon the backs of the vertical arms 16. The back fork ends 22 have one of the fingers 22' extending rearwards and passing through openings 62 formed in the bottom portions of the slides 60. With this construction when the back ends of the seat support members 20 are tilted upwards, the slides 60 will be forced upwards and will elevate the seat back 18. Pivot screws 63 are attached by chains 64 to the front ends of the seat support members 20. There is one pivot screw 63 for each seat support member 20. In the bottom positions of the seat support members 20 these screws 63 may be engaged through openings 65 in the forked ends 21 and in the vertical arms 15 in order to pivotally connect the front ends of the seat support members 20

with the vertical arms 15. Preferably, one of the openings 65 is formed with threads 66 engageable by complementary threads 67 of the screws 63 by which the screws 63 may be held in position.

The telescopic member 35 is connected with the seat support member 20 in a certain way, see Fig. 6. This way includes a lug 10 projecting from the seat support member 20 through which screws 71 engage and by which the telescopic member 35 is rigidly connected with the seat support member 20. This connection is used when it is desired to elevate the seat 23. However, when it is desired to tilt the seat 23 it is necessary that the screws 71 be removed. The top of the telescopic member 35 rigidly supports a pintle 72 welded in position which slidably engages a bracket 73 mounted from front to back upon the seat support member 20. Now when the telescopic member 35 is elevated by the jack 38, the pintle 72 is capable of sliding along the bracket 73 so as not to interfere with the arcuate path of the seat support member 20 during the tilting of the seat 23.

The top ends of the support arms 52 and 53 are connected with the other seat support member 20 in a certain way, as clearly shown in Figs. 11 and 12. More particularly, the upper ends of the support arms 52 and 53 are engaged through tubular bearings 75. Pintle pins 76 are rigidly mounted on the top of the tubular bearings 73 and slidably engage brackets 77 mounted from front to back upon the seat support member 20. Screws 78 normally engage through the seat support member 20 to the sides of the pintles 76 to normally hold the pintles 76 from sliding along the brackets 77. The screws 78 threadedly engage the tubular bearings 75 and hold them stationary. This permits the seat support member 20 to be elevated during vertical elevating of the seat 23. However, when it is desired to pivot the seat 23, the screws 78 are removed. Now the pintles 76 may slide along the brackets 77. Each pintle 76 is provided with an enlarged head 79 engaging along one of the sides of the brackets 77 to hold the pintles 76 from accidentally disengaging from the brackets 77. Now the support arms 52 and 53 may be elevated for tilting the said seat support member 20.

The operation of the new foldable wheel chair may be understood from the following:

In Figs. 1 to 2 the wheel chair is illustrated in a condition in which the seat 23 thereof may be elevated and then moved downwards. To elevate the seat 23 it is merely necessary for the person sitting on the seat 23 to move the jack handle 43 forwards and backwards so as to cause the jack 38 to operate to extend the telescopic member 36 thereof. When the member 36 moved upwards, the telescopic member 35 will move one of the seat support members 20 upwards, and simultaneous the support arms 52 and 53 which are supported by the downwardly extended arm 50 rigidly connected with the telescopic member 36, will move the other of the seat support members 20 upwards. This elevates the seat 23. Fig. 14 illustrates in full lines a half way elevated position of the seat 23. The seat 23 may be elevated until it strikes the arm rests 14. This elevating action permits a handicapped person to raise himself to reach objects normally out of reach. The seat 23 may be lowered merely by turning the knob 46 so that the cable 45 operates the valve connection 47 of the jack 38 to release the fluid

which elevated member 36. Then the weight of the person will cause the telescopic member 36 of the jack 38 to move downwards and the seat 23 will be moved to its lowered position.

5 The wheel chair may be narrowed so that it may pass through narrow doors, as follows: The person sitting on the seat 23 merely turns the hook 55 to the position 55' illustrated in Fig. 6 so as to extend beneath the slide member 30. 10 Now the jack handle 43 is manipulated to operate the jack 38 so as to cause the telescopic member 36 to move upwards. The hook 55 will drag the slide member 30 upwards. Upward motion of the slide member 30 will be communicated by the crossed arms 25 to the side frames 10 causing the side frames 10 to be drawn towards each other and in this way narrowing the wheel chair. The chair may be narrowed to a position in which the side frames 10 press against the buttocks of the person in the chair. This represents the narrowest position of the chair. The wheel chair is widened again to its normal position merely by operating the knob 46 to cause the cable 45 to adjust the valve connection 47 of the jack 38 15 so that the weight of the person on the seat 23 causes the telescopic member 36 of the jack to move downwards. In this way the seat support members 20 and slide members 30 are moved downwards and the crossed arms 25 will move the slide frames 10 outwards to their normal positions.

20 The seat 23 may be tilted to assist an arthritic person from a sitting to a standing position as follows: The pivot screws 63 are engaged through the opening 65 in the forked ends 21 and the vertical arms 15 in order to pivotally connect the front ends of the seat support members 20 with the vertical arms 15. Now the seat support members 20 are capable of pivoting upwards about the pivot screws 63 as centers. The screws 71 are now removed so as to free the pintle 72 in relation to the brackets 73. The screws 78 are now removed in order to free the pintles 76 in relation to the brackets 77. Now the jack handle 43 is operated in the usual way so as to extend the telescopic member 36 of the jack 38. This causes the support arms 52 and 53 to be also moved upwards. The pins 76 and 72 now slide in the brackets 77 and 73, respectively, lifting the back of the seat support members 20 in order 25 to pivot the seat support members 20. The seat support members 20 may be pivoted upwards to a position, for example, as illustrated in Fig. 14 by the dot and dash lines 20'. The extensions 22' of the forked ends 22 will simultaneously force the slides 60 upwards and in this way elevate the seat back 18 as indicated by the dot and dash lines 18' in Fig. 14. In the tilted position of the seat 23 and the raised position of the seat back 18, the person is assisted from a sitting to a standing position.

30 The foldable wheel chair is at all times free to be folded when desired. In order to fold the wheel chair it is merely necessary to lift the slide members 30 upwards and then press the side frames 10 together so that the side frames 10 move all the way together, as illustrated in Fig. 13. It should be noted that the telescopic member 35 is automatically moved upwards in relation to the telescopic member 36 during this folding operation. This extension is necessary in order to permit the wheel chair to be manipulated to its completely folded condition. It is further pointed out that the telescopic members 75 35 and 36 of the jack 38 are always free to be

extended since the fluid of a jack will not interfere with this action.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A foldable wheel chair, comprising a pair of side frames with wheels, a flexible seat back mounted between said frames, a slide member vertically slidably mounted on each of said frames, stops for determining the bottom positions of said slide members, a pair of crossed arms pivotally connected at their centers and having their bottom ends pivotally connected with said side frames and having their top ends pivotally connected with said slide members for controlling the folding together and opening of said side frames, a seat support member vertically slidably mounted on each of said frames immediately above said slide members, a flexible seat mounted between said seat support members, and means operable by a person sitting on said seat for adjusting said seat support members to various elevated positions for adjusting the elevation of said seat, said means including telescoping members which are free to extend at any time in order that said slide members may be moved completely upwards by said crossed arms to permit folding of said chair, said telescoping members including a jack mounted on one of said side frames and having its extendable telescopic member connected with one of said seat support members, and support arms pivotally connected with said extendable telescopic member and with said other of said seat support members.

2. A foldable wheel chair, comprising a pair of

side frames with wheels, a flexible seat back mounted between said frames, a slide member vertically slidably mounted on each of said frames, stops for determining the bottom positions of said slide members, a pair of crossed arms pivotally connected at their centers and having their bottom ends pivotally connected with said side frames and having their top ends pivotally connected with said slide members for controlling the folding together and opening of said side frames, a seat support member vertically slidably mounted on each of said frames immediately above said slide members, a flexible seat mounted between said seat support members, and means operable by a person sitting on said seat for adjusting said seat support members to various elevated positions for adjusting the elevation of said seat, said means including telescoping members which are free to extend at any time in order that said slide members may be moved completely upwards by said crossed arms to permit folding of said chair, said chair including means for rigidly connecting an adjacent pair of said slide members and said seat support members for partially closing said side frames when said seat support members are adjusted upwards.

3. A foldable wheel chair as defined in claim 2, in which said means for rigidly connecting said members comprises a hook on one of said members engageable with the other of said members.

MONROE ARNOLD LERMAN.
